UNITED STATES PATENT OFFICE.

ELMER A. SPERRY, OF BROOKLYN, NEW YORK.

SHIP'S GYROSCOPE.

1,150,311.

Specification of Letters Patent.

Patented Aug. 17, 1915.

Application filed May 21, 1908. Serial No. 434,048.

To all whom it may concern:

Be it known that I, ELMER A. SPERRY, a citizen of the United States, residing at Brooklyn, in the county of Kings and State 5 of New York, have invented new and useful Improvements in Ships' Gyroscopes, of which the following is a specification.

My invention relates to gyroscopes, particularly as applied to bodies in normally 10 stable equilibrium but susceptible to oscillations,—as ships, for example.

Certain subject matter in this application,—such as the broad idea of a controllable mechanical precession for a gyroscope; 15 the primary actuator or controlling pendulum; the combination of an artificially precessed gyroscope with a body in stable equilibrium; and the application of gyroscopes to rolling as well as to stabilizing 20 ships,—is disclosed in my application Ser. No. 411,017, means for imparting stability to or moving ships or other bodies, filed Jan. 15, 1908, and is continued in this application.

25 It has been known that gyroscopes mounted in swinging frames pivoted in a plane transverse of a ship would reduce the rolling to some extent,—the remaining roll of the ship being depended upon to give the motion to the gyroscope by which, through gyroscopic forces, its frame was caused to swing fore-and-aft, to create the transverse stabilizing forces. Such apparatus was sluggish, did not act effectively until the 30 ship had acquired considerable momentum, and hence was only partially successful in dampening the rolling. It was entirely ineffective in causing the vessel to roll artificially, in cases where that was desirable.

40 One object of my invention is to provide means whereby the necessary swing of the gyroscope frame is produced without waiting for the roll of the ship or other body to appreciably develop, so that the gyroscope becomes active promptly on incipient rolling and usually continues to exert its effect until the ship rolls back in the other direction.

To attain this I swing the gyroscope frame mechanically and under perfect control.

Since the precession is mechanically produced and controlled, my apparatus may be used either to suppress the natural rolling

of the ship, or to cause a ship to roll artificially, as may be desirable.

55

In connection with bodies in unstable equilibrium small gyroscopes have been used in which the precession was accelerated artificially by the use of falling weights or by pressing the rapidly rotating spindle of 60 the gyroscope wheel against a rack or friction surface, in order to continually reverse the falling motion of the unstable body,—by throwing it to one side and the other of the central position. The violence of the swing 65 thus imparted made the use of such means inapplicable to large gyroscopes; and the system could only be used with bodies in unstable equilibrium since the precession was always accelerated and the resulting 70 righting impulse of very brief duration. The briefness of the precession movement, together with the fact that it was out of phase with the movement of the body, made the system totally inapplicable to bodies like 75 ships, which are in normally stable equilibrium and susceptible to prolonged oscillations. The problem which I attacked was not to balance an unstable body, but to do this, I make a mechanical precession substantially in phase with the oscillations of the body.

80

Accordingly another object of my invention is to make a mechanically controlled 85 gyroscope which may be used with large bodies as well as small; which I attain by controlling the swing of the gyroscope frame both as to speed and duration, through motor means which may operate 90 without shock and with any desired velocity,—either greater or less than the free precessional velocity. In short, I provide a fully controllable precession. And further, in order that my gyroscope may be applied 95 to control oscillations of stable bodies, I arrange an automatic controller to operate the precession engines substantially in phase with the oscillations of the body,—so that for example, when a ship is having a motion 100 in oscillation, the precession engines will continually energize the gyroscope; and at the moments when the ship ceases to have such motion, the precession engines will cease to energize the gyroscope.

100

105 Other objects of my invention are to pro-

vide means for swiveling the entire gyroscope structure so that it may be operated in any desired direction; for locking it in the desired position; for locking any or all 5 of the swinging frames whereby the gyroscope may be made idle, (incapable of doing work), partially or wholly.

Further objects are to provide sensitive 10 automatic means for energizing the controller, and an intermediate control drum by which the gyroscope may be made to perform any desired movements.

The means I employ are briefly (1) a 15 gyroscope pivoted to oscillate or precess relative to the body, (2) motor means producing or controlling the precession of the gyroscope,—the motor means being susceptible of regulation and definite control, so that the duration and intensity of the 20 stresses are controlled, (3) a controller, preferably automatic, for the precession motor, operating it in step with the movements of the ship or other body so that natural oscillations of the ship may be either 25 created or suppressed. To simplify the description the above elements will be analyzed separately and then their conjoint operation will be shown.

In the drawings forming a part of this 30 specification, Figure 1 is a view of a gyroscope mounted on a swivel base. Fig. 2 is a vertical section of a preferred embodiment of the invention, parts being shown in elevation. Fig. 3 is a diagrammatic elevation of a modified form. Fig. 4 is a plan view of 35 means for operating two gyroscope sets. Fig. 5 is an elevation of a controlling pendulum. Fig. 6 is an elevation of a further control apparatus.

40 Similar reference characters refer to like parts throughout the several views.

To make the gyroscopes operate automatically,—on shipboard for example,—a device responsive to the motion of the ship 45 (especially the incipient motion) must be provided, in order that the motors be energized in the proper manner as the ship rolls. The device must be sensitive yet powerful enough to be able to operate switches, valves 50 or other controlling means for the motors. Any suitable means might be used, and I will now describe one form of inertia device of the pendulum type which I prefer.

55 Referring to Fig. 5, a pendulum rod 45 is provided at its lower end with a heavy weight 46. The pendulum may be locked when desired by the pin 48 being engaged by the sleeve 49 which is vertically slidable in the fixed sleeve 47. Normally, however, 60 the pendulum hangs freely so as to maintain a steady vertical position irrespective of the motion of the ship. To this end it is hung from the pivots 50, whose axis is longitudinal of the ship,—the pivots 50 being 65 in turn supported in the ring 51 which is

pivotedly mounted at 53—53 on a transverse axis, by means of the lugs 52—52 which are fixed to the ship. This provides a universal mounting for the pendulum, so that it is not affected by rolling or pitching of the 70 ship. Fixed to the swinging ring 51 are hangers 54 connected by the cross-bar 60,—the hangers 54 supporting all of the primary control devices except a small contact button 55 and its battery lead. 75

In detail,—fixed to one of the hangers 54 is a reversible double-field motor 66, which through worm gearing drives the worm wheel 67, keyed to the shaft 59. The shaft 59 is mounted in suitable bearings at the 80 ends of the hangers 54 and carries a friction drum 71.

Frictionally mounted on the drum 71 is the conducting band 70,—the degree of friction being adjusted by the clamping screw 85 72. The band 70 carries the contact switch finger 73 which swings between the contact plates 74 and 75,—the contact plates forming the two poles of a reversing switch, by means of which the operation of the stabilizing gyroscopes is ultimately controlled. 90

One terminal of a suitable source of electricity B is connected to the pendulum rod 45 which carries the contact button 55. Spring contacts 56—57 coöperate with the 95 two sides of the button 55, and are carried on a traveling sleeve or nut 58 which is internally screw-threaded to correspond to the threads on the shaft 59. These threads on the shaft 59 are preferably of long pitch so that, for example, one turn of the screw 59 would cause the nut 58 to travel from one 100 end bearing to the other. The sleeve or nut 58 is longitudinally guided and prevented from rotation by guides sliding on the cross-bar 60. The two contacts 56 and 57 are each 105 connected to their respective terminals on the reversing double-field motor 66, to which is also connected the other terminal of the source of electric current B. Thus if the button 55 swings against the contact 56, the motor 66 will be run in one direction, and if the button 55 swings against the other contact 57, the motor 66 will be run in the other direction. 110

115 Since the pendulum 45 is universally supported on two sets of pivots, it is unaffected by either rolling or pitching of the ship; while the hangers 54 and their attached parts, having only the transverse pivots 53—53, must roll with the ship, though unaffected by the pitching of the ship. Hence both parts of the apparatus are unaffected by the pitching of the ship, but the frame 54—54 and its attached parts will move 120 relatively to the pendulum 45 to the extent that the ship rolls. 125

The operation of the inertia device or controlling pendulum as applied to either 130 causing or suppressing the rolling of a ship 133

is therefore as follows. Assume the locking sleeve 49 pulled down and the pendulum 45 to be hanging free as shown; when the ship rolls to the right the lugs 52-52 and 5 pivots 53-53, together with the hangers 54-54 and all their attached parts, will be turned in a clockwise direction,—while the pendulum 45 and its contact button 55 hang stationary. This, at the very beginning of 10 the roll, will cause the spring contact 56 to press against the button 55, completing one of the circuits through the motor 66, and causing it to drive the worm wheel 67 in a direction to cause the nut 58 to travel toward the right. The speed of travel of the 15 nut 58 is arranged to be greater than that of the button 55 relative to the contact 56, so that the slightest contact at 55-56 will cause the nut 58 to move to break the contact. Thus the nut 58 will be fed along at 20 the same rate as the button 55 moves, yet there will be no appreciable pressure between the button 55 and the contact 56 so that the pendulum 45 will continue to be 25 undisturbed in its vertical position in space. Conversely, when the ship starts to roll to the left, the connection will be made between the button 55 and the contact spring 57, which will complete the other circuit of 30 the motor 66, to run it in the reverse direction, and turn the shaft 59 to feed the nut 58 toward the left. In this manner the part 35 58 will be seen to follow delicately the movements of the pendulum 45 in either direction and always stand in readiness to be responsive to a minute but predetermined movement. The contacts 55, 56 and 57 are made when the pendulum has moved relative to the body through a small and almost 40 inappreciable arc, which may be known herein as representing the incipient movement or oscillation of the body or ship.

Since the shaft 59 turns in one direction or the other according as the ship rolls, the 45 comparatively heavy contact finger 73 will be swung forward or back because of the friction of the band 70 on the drum 71, as the latter is turned by the shaft 59. Thus as the ship rolls to the right, the shaft 59 50 will turn so as to swing the finger 73 back against the contact 75,—continued motion of the shaft 59 merely turning the drum 71 frictionally in the then stationary band 70. The electric current is then led through the 55 contact switch finger 73 to the contact and wire 75,—the contact switch finger 73 being connected to a suitable source of electricity, as the switch 123, Fig. 6. When the ship starts to roll to the left, the rotation of the 60 shaft 59 in the opposite direction,—through the reversing of the motor 66,—causes the finger 73 to be swung out against the contact 74. Hence as the ship starts to roll to the right a strong electric current can be 65 conducted through the wire 75', and when

the ship starts to roll to the left the current through 75' is broken and the current is then conducted through the wire 74'. The contacts 74 or 75 are maintained so long as the swing of the ship continues.

Thus I have provided a means whereby a strong electric current may be reversed in accord with the reversing of the roll of the ship,—the means being sensitive in action yet unaffected by undesirable external influences which might cause periodic disturbances. Instead of connecting the wires 74 and 75 directly to the precession motor or motors, which would involve heavy currents passing through the simple controller above 80 described, this controller operates the motors through a relay or intermediate controlling device which is adapted to start and stop the flow of energy to the precession motors. Where complex movements or series of movements are desired to be automatically performed, the intermediate device or relay may be of the drum controller type as shown in Fig. 6,—the drum controller operating to drive the motors in one 85 direction or the other according as the electric current is received through the wire 74 or wire 75. The conducting bands on the drum of such a controller may be spaced so that they will pass under the brushes in any 90 desired sequence, so that the motors and brakes of the gyroscope may be energized and deenergized in any prearranged sequence. An example of such a controller will be described in connection with the 100 more complex operations which the gyroscope may perform.

I have now shown means whereby the motive fluid of the gyroscope's engines and brakes is automatically supplied and controlled according to the roll of the ship. I will now proceed to describe a preferred form of gyroscope with means for controlling the same.

Fig. 1 shows a simple model with manual control adapted for demonstration purposes to illustrate gyroscopic principles. It will be first described in order to assist in the understanding of the more complex device shown in Fig. 2.

Secured to the structure 18 which is to be steadied is the pivot pin 99, on which is swivelly mounted the base 17' of the lower gyroscope frame 17. This base 17' is shown as held from turning by the lugs 45'-46' 120 engaging the pin 46'', which may be set in any one of the holes 47''. The base 17' may accordingly be locked in any position, or may be rotated by the handle 43 through any desired angle,—as 180° for example. 125 Branching up from the base 17' are the two arms 17-17 which carry the base ring 15 pivoted at 16-16. The base ring 15 may be tilted by the handle 44, and carries the rotor ring 27 pivoted at 28-28, at right 130

angles to the pivots 16—16. In the rotor ring 27 is the gyroscope rotor or flywheel 34, carried on the shaft 35, and spun by the motor 36. The rotor ring 27 may be locked by the band brake 40 attached through the extensions 41 to the base ring 15 at 42. A similar brake 41' may obviously be applied to any of the frames, as for example, to lock the base ring 15 the brake would be fastened to the arm 17; and to lock the swiveling base 17' the brake would be attached to the fixed base 18. We thus have a gyroscope mounted to turn on three mutually perpendicular, intersecting axes, so that it may be given any desired motion in any desired direction, and means for moving and locking it. With such an apparatus the behavior of the gyroscope under any possible precessional movement may be ascertained.

20 Fig. 2 shows a similar gyroscope of universal application but provided with suitable means for moving or locking the three pivoted frames. Here, as in Fig. 1, the numeral 18 refers to the structure to which the gyroscope is secured and against which its force ultimately acts, as for example the frame or deck of a ship. The location of the gyroscope mechanism in the ship is immaterial from a mechanical standpoint,—since by the laws of mechanics a given torque couple has the same torque effect on a turning body irrespective of the distance from the center about which the body is turning. The location of the gyroscope plant is then in practice determined solely by considerations of convenience. To this frame or deck 18 is secured the fixed base 80, having the pivot pin 99. Rotatably mounted on the pin 99 is the swiveling base 17', supported by the roller thrust bearings 114 under the flange 109. The movements of this swiveling base 17' are controlled by the rack bar 103 turning the pinion 104 which is fixed to swiveling base 17'. The roller 110 serves to hold the rack bar 103 in mesh with the swivel pinion 104, and the rack bar is moved and locked by any suitable means, as for example, the hydraulic cylinder 101 and the piston rod 102 shown in Fig. 4, controlled through the valve chest 111 and valve rods 112.

Rising from the swiveling base 17' are the arms 17—17, to which is pivoted at 16—16 the base ring 15, (shown in section), which extends in Fig. 2 horizontally around the rotor 34, just as in Fig. 1. Pivoted within the base ring 15 is the rotor ring 27, extended in Fig. 2 into a frame which envelopes the rotor 34, this rotor ring or frame 27 being pivoted at 28—28 to the base ring 15,—the pivotal axis 28—28 being at right angles to the pivotal axis 16—16, and both being at right angles to the pivot axis 99.

65 In order to move and lock the base ring

15 there is attached to it on the left hand side of Fig. 2 a downwardly extending arm which terminates in a gear segment at 15' which engages with the teeth of a gear 98, the latter being rotatably mounted on the upper part of the pivot pin 99. The gear 98 is keyed to the motor 97, having a commutator 117 by which the current is led into the motor, and magnetic brakes 100 by which the motor 97,—(and consequently the gear 98 and frame 15),—may be locked against motion when desired. The gear segment on the arm 15' is held in contact with the gear 98 by means of the roller 115. Means are thus provided to move and lock 80 the base ring 15 as desired.

In order to move and lock the rotor ring or frame 27, which is pivoted at 28—28, there is provided the gear segment 95 secured to the frame 27 by the arms 95'. This gear segment 95 meshes with the bevel gear segment 96, which is pivoted at right angles to the gear 95 by means of the trunnion 16' which is journaled to turn freely within the main pivot bearing 16. The gear segment 96 is operated through a depending arm which curves down and terminates in the gear segment 81 whose teeth mesh with the teeth of the gear 98, rotatably mounted on the upper end of the fixed pivot 99, (independent of the gear 104), and driven and controlled by the motor 97 and magnetic brakes 100, as described. Readily controllable means are thus provided to operate the gears controlling the swing of the rotor frame 27, in which the rotor or flywheel of the gyroscope is journaled. This rotor or flywheel of the gyroscope, from which the stabilizing forces are obtained, consists of a heavy, carefully balanced wheel 34 carried by the shaft 35 which is journaled in suitable lateral and thrust bearings in the frame 27 and rotated at a high but safe speed by the motor 36. The rotating parts are preferably inclosed in a vacuum casing 113, in order to reduce the air friction, and to keep the motor 36 from overheating, the radiating fins 116 are provided. The bearings are lubricated by suitable means, as for example the oil cup 44'. The electric current 110 to operate the various motors and brakes is led in through the individual slip rings indicated diagrammatically at 128—130,—thus permitting the motors and brakes to be operated when the gyroscope is turned 120 in any direction.

While I have above described a controlling mechanism operated by electricity, it is to be understood that any type of motor or engine may be used provided that it is susceptible to a nice control. The fact that a slight movement of the gyroscope frames creates powerful gyroscopic forces makes an indefinite control dangerous. Fig. 3 for example shows the control engines of the pis-

ton type, such as are operated by hydraulic or other fluid pressure. Only the active parts are shown in Fig. 3, for the sake of clearness. In that figure, the rotor ring 27 which carries the rotor 34 on the shaft 35 is pivoted in the bearings 28-28 of the base ring 15, which in turn is pivoted at right angles to the pivots 28-28 at the pivots 16. The base ring 15 is oscillated by the piston rod 108 driven by the piston in the cylinder 107, and braked or locked by the cylinder 105. The rotor supporting ring 27 is oscillated by the bevel gear 95 secured thereto, which in turn meshes with the gear segment 96 which is pivoted in the bearing 16' turning freely within the bearing 16. The gear segment 96 is driven through the piston rod 118 by an individual cylinder 106,--as distinguished from Fig. 2 where the single motor 97 operated both frames. For the purposes of economy the cylinders 105 and 106 are cross-coupled, in order that the fluid used as a brake in one may be used to drive the other. If it is desired to omit the swiveling feature of Fig. 2, the frame 17, (shown broken away in Fig. 3), together with the operating cylinders 105 and 106 may be secured to the deck or frame of the ship 18 as shown in Fig. 3. But if the swiveling feature is desired, the cylinders 105 and 106 may be secured to the swiveling pedestal 17' as is done with the operating motors in Fig. 2.

In Fig. 4 means are illustrated for swiveling and locking the gyroscope. It is shown as applied to a pair of gyroscopes. The use of a pair of gyroscopes prevents the steering being affected, as is well known,— the rotors spinning in opposite directions so that when the ship turns they counteract each other. The view in Fig. 4 is a horizontal section taken through the gear 104 of Fig. 2, which it will be recalled is secured to the gyroscope frame 17'. The fixed pivot 99 on which the gear 104 turns rises from the base 80 which is secured to the ship. The thrust plate or flange which supports the weight of the gyroscope structure is indicated at 109. Cooperating with the gear or pinion 104 is the rack bar 108, connected to the piston rod 102, driven by the cylinder 101. The fluid in the cylinder is controlled by suitable valves in the valve chest 111, operated by the valve stems 112. The roller bearings 110 hold the racks 103 in place. The mechanism of the two sets shown in Fig. 4 is identical.

I have now described mechanism sensitive to the roll of the ship which releases energy, the direction of the flow of energy being reversed as the roll of the ship reverses. I have also shown means adapted to receive this energy, or a relay thereof, and to apply it through definitely responsive yet powerful engines to the frames which swing

the gyroscope flywheel,—that is, which cause the axis of the gyroscope rotor to precess.

I will now describe the principles on which the gyroscopic force is created which may operate to stabilize a ship or to exert a torque for any other desired purpose. Considering first Fig. 1, assume the rotor 34 to be spinning counter-clockwise as viewed from the top,—that is, the near side of the wheel to be moving toward the right. Then if the top of the rotor frame 27 is tilted to the right, the result will be a strong force tending to lift the near side of the base ring 15, and to depress the far side. That is, tilting of the axis of the gyroscope in the plane 16—35 creates a powerful torque or force-couple in the plane 28—35, which is at right angles to the first plane in which the original movement occurred. Conversely, tilting the top of the rotor frame 27 back toward the left will reverse the direction of the torque or force-couple on the base ring 15, depressing the near side and raising the far side of the base ring 15. Thus it is clear that if the base ring 15 were connected with a ship, then the fore-and-aft tilting of the rotor ring 27 would develop a transverse torque on the base ring 15 which might be used to oppose the roll of the ship.

Still considering Fig. 1, if the rotor ring 27 is left free, (except as partially retarded by the brake 40), and the base ring 15 is depressed on the near side, the top of rotor ring 27 will swing strongly to the right. Such movement to the right by the ring 27 causes a lifting force on the near side of the base ring 15, as stated in the preceding paragraph. The result is that when we depress the base ring 15, the ensuing tilt of the rotor ring 27 causes a force on the base ring 15 tending to lift the depressed side. Thus if applied to stabilizing a ship, with the axis 16-16 fore-and-aft, and the axis 110 28-28 transverse of the ship as before stated, then if the ship started to roll downward on the near side, swinging the top of the gyroscope toward the observer, the roll would be opposed by depressing the near 115 side of the ring 15 and swinging the top of the ring 27 toward the right. The mere fact that the ring 15 was rotated in the direction that the ship rolled would tend to steady the ship, since the reaction torque 120 would be in the opposite direction to the roll,—action and reaction being equal and in opposite directions. But the main stabilizing torque would be due to the swing 125 of the ring 27 toward the right. The resulting torque due to the movement of the latter ring is very powerful, and tends to twist the base frame 15 and the whole gyroscopic structure away from the observer, thus steadyng the ship. The principal advan- 130

tage of depressing the base ring 15 at all is to thus aid the motors which tilt the rotor ring 27,—since the depressing of the near side of the base ring urges, (through the described gyroscopic effect), the rotor ring 27 in the same direction in which the precession motors would be moving it.

When the ship rolls in the other direction, the direction of movement of all the parts 10 should be reversed, as is evident. If the gyroscope in Fig. 1 had the frames 27 and 15 locked in the position shown, the whole structure could be swiveled on the base pivot 99 without developing any gyroscopic force. 15 Thus the set could be freely swiveled to act in any desired direction.

Referring now to Fig. 2, assume by way of example the rotor 34 to be spinning in a counter-clockwise direction as viewed from 20 above,—that is, the near side of the rotor 34 to be moving toward the right. If the device is to steady the rolling of a ship, assume the pivots 16—16 to be parallel to the longitudinal axis of the ship, which would 25 make the pivots 28 transverse of the ship. Now consider the actuator illustrated in Fig. 5, where the pivot lugs 52 are mounted transverse of the ship. When the ship rolls to the left in Fig. 5, or toward the observer 30 in Fig. 2, the actuator in Fig. 5 will send the current through the contact 74. This current, either directly or through a suitable relay, will energize the precession motor 97 to spin clockwise, as viewed from above. 35 The energy is led into the motor 97 from the outside source through the slip rings 130—128 and commutator 117, as has been described. The motor 97 turning as stated will rotate the gear 98 keyed thereto, so 40 that the teeth on the right hand side of the fixed pivot 99 move toward the observer. This will swing the meshing gear segment 81 toward the observer, thus rotating the attached gear 96 downward, which turns the 45 gear 95 and the attached frame 27 in a clockwise direction. Thus the rotor axis 35 in the frame 27 is tilted to the right. This gives the stabilizing force desired, since it tends to swing the structure away from the 50 observer, in the opposite direction to the assumed roll of the ship. Conversely, when the ship rolls in the other direction, the actuator shown in Fig. 5 operates to send the current through the contact 75, which 55 accordingly causes the motor 97 to rotate in the opposite direction, which through the gearing described, tilts the rotor frame 27 in the opposite direction, or to the left, causing the gyroscopic torque to be reversed, *i. e.*, 60 tending to swing the top of the structure toward the observer, and so opposing the backward roll of the ship.

Since the speed of the motor can be regulated, the rate and period of the precessional swing of the ring 27 can be adjusted,

and the strength and duration of the gyroscopic forces accordingly can be controlled. It is thus possible to use the gyroscope in powerful units, and so to stabilize ships.

To assist in swinging the rotor ring 27 70 the base ring 15 is provided. This base ring 15 is connected through the gear segment 15' to the left hand side of the gear 98. Then as the gear 98, driven by the motor 97, turns in a clockwise direction, 75 (viewed from above), so as to tilt the rotor frame 27 toward the right, (through the gears 81—96—95), the gear segment 15' will be swung backward, thus tilting the near side of the base ring 15 downward. But 80 the gyroscopic effect of depressing the near side of the base ring 15, as explained in connection with Fig. 1, is to urge the rotor frame 27 to swing to the right. Thus by gearing to the frame 15 as well as to the 85 frame 27, the gyroscopic reactions of the ring 15 are made to aid the gears on the frame 27 to swing the latter frame in the desired direction.

Since the tilting of the frame 27 to the 90 right or the left, fore-or-aft of the ship, creates a powerful unbalanced torque transverse of the ship, it is evident from the general law that action and reaction are equal that the torque so created must be absorbed 95 by the body to which the apparatus is attached,—namely, by the ship. Taking for example the case where the top of the ship rolls toward the observer, and the top of the rotor frame 27 is then tilted to the right by 100 the operation of the precession motor 97,—the effect of this tilting to the right is to create a strong torque in the gyroscope frame 27 tending to turn the top rotor bearing in the frame 27 away from the observer 105 and to swing the lower bearing of the rotor toward the observer,—in other words, to twist exactly opposite to the roll of the ship. But this twist or torque is resisted by the frames 15 and 17, and the arms connected 110 thereto, which not only do not allow the rotor frame to turn in response to its gyroscopic torque forces, but the whole structure is compelled to swing against the gyroscopic torque since it is secured to the rolling ship,—and the great gyroscopic torque 115 merely acts as a brake to resist or diminish the rolling of the ship.

When it is desired to cause the ship to roll artificially, the operation of the apparatus is precisely the same as has been described, though the direction of application of the gyroscopic forces is of course reversed. The apparatus here shown is 120 equally applicable to stabilizing or to rolling, depending on the direction in which it is run. The description has referred to the case of stabilizing merely for the purpose of illustration, and its uses are much more 125 far reaching.

The above effects which involve merely the starting and stopping of the motor 97 might be obtained without using any further controller than that illustrated in Fig. 5. But when more complicated operations are desired, a controller of a type suitable for operating a plurality of motors and brakes must of course be used. Such a controller is shown in Fig. 6. In the preferred form which I have shown in Fig. 2 the gyroscope is pivoted about three different axes, each at right angles to the other two, and the rotor may be swung about any or all of these axes, since each has its controlling motor and brakes. Thus, by suitable regulation of the motors, the gyroscope wheel may be given any desired precession in any desired direction, and the rotor may be tilted and swung into any plane whatsoever.

With this gyroscope, or one constructed on substantially the same principles, any and every gyroscopic effect may be obtained that is possible with a single gyroscope.

Fig. 6 shows how a controller of the ordinary drum controller type may be applied to a gyroscope set of the nature described to produce any desired series of motions. As is well known, a drum controller,—such as is used on street cars for example,—consists of a rotatable cylindrical drum having on its periphery a number of bands or segments of conducting material. Arranged usually along in a line are a series of stationary brushes which contact with the conducting bands or segments as the drum turns. The currents are generally led into the controller by brushes which contact with continuous bands or slip rings, so that their contact is not broken in any position of the drum.

The segments through which the operating current is drawn off are connected to the main bands or slip rings, and are made of such lengths that they will be in contact with their respective brushes for the desired length of time as the drum revolves. Such drum controllers are very flexible, since by suitably arranging the number of brushes and by suitably spacing the segments on the periphery of the drum, any number of brushes can be connected to the source of power in any predetermined sequence and for any predetermined period.

Such a controller may be adapted to a device such as a gyroscope, which must automatically reverse, by the means shown in Fig. 6. The drum of the controller is shown at 82, viewed from the end, and is continuously turned in a constant direction by the motor 89 driving the worm gear 90 through the worm wheel 90*. This motor 89 is connected through the switch 119 and contact 124 to a source of electrical energy, marked +. The same switch has another contact 123 from which the electric current is led as described in connection with Fig. 5

to the contact finger 73, shown in both Fig. 5 and Fig. 6. The finger 73 swings against either the contact 74 or 75, depending on the action of the primary actuator shown in Fig. 5. The contacts 74 and 75 are connected by the wires 74' and 75' respectively with a pair of brushes which contact with separate conducting bands surrounding the periphery 76 of the controller drum, and respectively connected with the brushes 77' and 76' at each end of the drum, which lead down through the arms 62 and 61 respectively to the magnets 79' and 78'. Thus when the contact finger 73 swings in one direction the magnet 79' is energized, and when the contact finger 73 swings in the other direction the magnet 78' is energized.

The magnets 79' and 78' serve to tilt a base 86 about the pivot 87 to the right or the left, the tilting base being held in its extreme position in either direction by the spring 88, whose roller tip coöperates with an extension of the tilting arm. Mounted on the tilting table 86 are two sets of brushes 84 and 85, arranged on opposite sides of the controller drum 82. Each numeral 84 and 85 represents a whole set of brushes extending axially along the drum, each brush being connected with the motor, brake, or whatever mechanism it is to control. At 83 is shown the main brush or pair of brushes which continually contact with bands or slip rings on the drum connected with the various conducting segments for the sets of brushes 84 and 85. The sets of brushes 84 and 85 alternately engage the segments on the drum as the table 86 is tilted,—for example, when the contact 74 is made and the magnet 79' is energized, the brushes 84 are swung into contact with the drum, while the brushes 85 are swung out of contact. Conversely, when the magnet 78' is energized through the contact 75, the tilt of the base 86 will throw the brushes 84 out of contact with the drum and the brushes 85 into contact. By arranging two sets of brushes in this manner, so that either set may be automatically thrown into contact with its segments on the controller drum, it is evident that by appropriately arranging the conducting segments and brushes any desired series of connections on the drum may be made when one set of brushes is in contact, and this series may be repeated with a reversed direction of current flow by interchanging the poles when the other set of brushes is in contact. While one set of brushes remains in contact with the drum, the period during which any particular brush will receive current will of course depend on the length of the segment which it touches and the speed of rotation of the drum. So by adjusting the speed of the motor 89, the operations controlled by the drum may be made to occur with any desired rapidity,—while the relative dura-

tion of the periods of the individual brushes will be determined by the relative lengths of the segments on the periphery of the controller drum. In cases where the period of oscillation of the oscillating body is known, the control may be effected by rotating a controller cylinder after the manner of 82 synchronously with the period of oscillation.

Having shown how by an adaptation of 10 the ordinary drum controller any number of motors, brakes, valves, etc., may be controlled by merely connecting them to the various brushes which are energized by the controller drum,—and how consequently 15 such motors, brakes, valves, etc., would be operated in any predetermined sequence according to the law of the controller, I will now follow the operation of a gyroscope in which such a control is utilized. For example, 20 it is possible to have the gyroscope shown in Fig. 2 operate in one plane, and then return through different planes to its original starting point.

To follow such a series of operations, assume 25 the rotor 34 to be spinning in a counter-clockwise direction as viewed from above,—that is, the near side of the rotor 34 to be moving toward the right. Then assume the drum controller to be turned so as 30 to cut off the electric current to the brushes controlling the brakes 100, and another contact to be made with the brushes energizing the motor 97 to rotate in a clockwise direction about the pivot 99, as viewed from 35 above. This would turn the right hand side of the gear 98 outward and the left hand side inward. The gear segment 15' meshing with the left hand side would be swung inward, depressing the near side of the base 40 ring 15, and swinging the top of the rotor spindle toward the observer. Simultaneously the gear segment 81 meshing with the right hand side of the gear 98 is swung outward turning the gear 96 about the pivot 45 16' in a counter-clockwise direction as viewed from the left, and turning the meshing bevel gear 95 in a clockwise direction. The rotor frame 27 being secured to this gear 95, must then be tilted,—the top swinging 50 toward the right. As has been previously described, the result of these motions is to create a powerful torque on the whole system tending to swing the top back away from the observer. By making the 55 gear faces sufficiently long, such motion might be continued through 90°, 180°, or 360°, but there is little practical use in allowing more than 180° swing,—or 90° each way from the mid position shown in Fig. 60 2,—since the stabilizing forces as applied to a ship would cease to act when the rotor axis became parallel to the longitudinal axis of the ship.

In the case under discussion, having al-

lowed the described motion to continue for 65 a swing of substantially 90°, the controller drum 82 would have meanwhile turned so that the brushes leading to the motor 97 would no longer engage their segments on the controller drum, thus stopping the motor 70 97; while other segments on the controller drum 82 would at the same time engage brushes to apply the magnetic brakes 75 100. The rotor and base frames 27 and 15 are thus locked in place, with the rotor axis 80 substantially horizontal. During all the above operations the gear 104 controlling the main frame 17 has been locked against rotation by the rack 103 held by the hydraulic pressure in the piston 101, (Fig. 4). 85 The controller drum 82 now being moved to energize any suitable means for the valve rod 112, the valves in the valve chest 111 will be opened to vary the fluid pressure in the cylinder 101, moving the piston rod 102 and 90 rack 103, and turning the gear 104 on the fixed pivot 99, thus turning the main frame 17 and the whole gyroscope structure in either direction as desired. After this motion has continued for 180°, the valve stem 95 112 can again be operated, stopping the flow of fluid in the cylinder 101, and so locking the main frame 17 from further movement. The swiveling movement around the pivot 99, if made while the base 80 is stationary, 100 will require very little power, since there would be no opposing reaction. Now the upper end of the rotor spindle 35, which under the first operation had swung to the right of Fig. 2, will be found at the left of 105 Fig. 2. If the brakes 100 are now released and the motor 97 operated in the reverse direction, (counter-clockwise as viewed from above), the frames 15 and 27 will move as before,—the near side of the base ring 15 110 being depressed and the top of the rotor frame 27 swinging toward the right. This would repeat the former stabilizing force tending to swing the top of the structure away from the observer, since the movement 115 of the gyroscope rotor in space is precisely as under the first swing. This last swing however may be of twice the duration of the first swing, since it may turn through 180°; or if the duration is made the same, the 120 force would be doubled due to the double velocity of the swing. If the roll of the ship had reversed at any time, the other set of brushes, 84 or 85, on the controller drum 82 would have been swung into contact, and the direction of all the motors, pistons, etc., controlling the gyroscope would be reversed, thus reversing the direction of the gyroscopic stabilizing reaction.

Many other complex movements may be 125 obtained from the apparatus shown in Fig. 2, as will be evident to those skilled in the art. The form shown in Fig. 3, not being

pivoted, is not of such general application, but may be used as well as the form shown in Fig. 2 for most practical purposes.

While I have throughout this specification described in more or less detail certain specific embodiments of my invention, I do not wish to be understood as limited to the particular forms here shown, as many adaptations of the fundamental combinations will be evident to those skilled in the art. Though the invention has been particularly described,—for the purpose of illustration,—as applied to stabilizing a ship against rolling in a seaway, it may also be useful at times to give ships a rolling motion, as in disengaging and withdrawing from rocks and ice-floes, working off sand and mud bars, breaking through ice, life saving, elevating battleship gunfire, coaling, amusement purposes, and various other purposes as will occur to those familiar with the handling of ships. The uses of the device are not limited to ships however, and it may be applied to any body having a substantially periodic oscillation, for either creating or suppressing such movements. My invention should be understood as covering all adaptations and variations such as fall within the scope of the appended claims.

30 I claim—

1. Means for applying a torque to a mass capable of a natural oscillation, comprising the combination of a gyroscope mounted to precess in a direction transverse to the plane of oscillation of the mass, controllable means for precessing the gyroscope, and a controller which automatically reverses the action of the controllable means in synchronism with the oscillation of the mass.

40 2. In a gyroscopic mechanism for oscillating structures, a gyroscope pivotally supported to swing relative to the oscillating structure, a precession engine capable of steady action for controlling the swing of the gyroscope, and an automatic controller for the precession engine.

3. In a gyroscopic mechanism for oscillating structures, a gyroscope mounted to precess relative to the oscillating structure, a precession engine for controlling the precession of the gyroscope, and means for reversing the precession engine at the beginning of each oscillation of the oscillating structure.

55 4. In a gyroscopic mechanism for a mass having an appreciable period of oscillation, a gyroscope mounted on said mass for precession relative thereto, motive means for controlling the rate of precession of the gyroscope, and an automatic controller for said motive means operating at the period of the oscillating mass.

60 5. In a gyroscopic mechanism adapted for a mass having extended periods of oscillation,

the combination of a gyroscope mounted on said mass for precession relative thereto, motive means controlling the precession and regulating means for the motive means arranged to extend the period of precession through the period of oscillation. 70

6. A gyroscope, in combination with a precession engine having a constant rate of precession through appreciable periods, for controlling the precession.

7. The combination of an oscillating mass 75 in stable equilibrium, a gyroscope mounted to apply torque to the mass, and means for mechanically causing the precession of said gyroscope.

8. In combination with a mass normally 80 stable but subject to oscillation, a gyroscope pivoted for precession relative to said mass, and motive means for precessing the gyroscope.

9. In combination with a mass normally 85 stable but subject to substantially periodic oscillation, means for applying a torque to said mass comprising a gyroscope mounted for precession relative to said mass, and means for starting the active precession of 90 the gyroscope before the oscillating mass has attained an appreciable velocity.

10. The combination of a gyroscope adapted to be mounted on an oscillating mass for precession relative thereto, motive 95 means for precessing the gyroscope, and power absorbing means for opposing the precession of the gyroscope.

11. The combination of a gyroscope mounted for precessional movements, power 100 means for aiding the precessional movements, and means for opposing the precessional movements.

12. The combination of a mass subject to oscillations, a gyroscope adapted to be 105 mounted on the oscillating mass for precession relative thereto, power means for aiding the precessional movements, means opposing the precession, and means operated by the oscillation of the mass for automatically controlling the power means and the opposing means. 110

13. The combination with a body capable of oscillation, of a gyroscope mounted upon said body, power operated means for causing and controlling the precession of the gyroscope, and an automatic controller for energizing the power operated means at the beginning of each movement of oscillation of the body. 115

14. A gyroscope pivotally mounted for precessional movements, means energized by a motive fluid for causing and controlling the precession of the gyroscope, and automatic actuating means controlling the flow of the 120 energizing motive fluid.

15. The combination with a body subject to oscillation, of a gyroscope pivotally

- mounted thereon for precessional movements, means energized by a motive fluid for causing and controlling the precession of the gyroscope, automatic means controlling the flow of the energizing fluid and actuated by the oscillation of the body.
16. The combination with a body subject to oscillation, of a gyroscope pivotally mounted thereon, a precession engine causing and controlling the precession of the gyroscope, means controlling the flow of energizing fluid to the precession engine, and an automatic actuator operating the controlling means, the actuator being operated by the oscillation of the body.
17. The combination with a body subject to oscillation, of a gyroscope pivotally mounted for precessional movements thereon, power operated means controlling the precession and adapted to start the precession at the beginning of an oscillation of the body, to stop the precession when the movement of the oscillating body stops, and to start the precession in the reverse direction at the beginning of the return swing of the oscillating body.
18. Means for applying gyroscopic forces to an oscillating vessel, comprising in combination controllable gyroscopic means for imparting an oscillating force to the oscillating vessel, and mechanism moving relative to the vessel whereby said means is caused to reverse its action upon the oscillating vessel at regular and predetermined intervals of time.
19. Mechanism for applying gyroscopic forces to an oscillating vessel, comprising the combination of a gyroscope, means for moving its spinning axis in a predetermined path with respect to the oscillating vessel and at intervals corresponding to the periodicity of the oscillating vessel.
20. Means for applying gyroscopic forces to an oscillating vessel, comprising the combination of a plurality of gyroscopes, and means, independent of the action of the oscillating vessel, for moving their spinning axes in a predetermined path with respect to the oscillating vessel and at intervals corresponding to the periodicity thereof.
21. Means for applying gyroscopic forces to an oscillating vessel, comprising in combination a gyroscope mounted in the oscillating vessel, a casing within which the gyroscope is capable of spinning and having trunnions extending from its sides the axis of which is at right angles to the spinning axis of the gyroscope, a bracket on each side in which is journaled one of the trunnions of the gyroscope casing, and mechanism for rocking the gyroscope casing upon its trunnions.
22. Means for applying gyroscopic forces to an oscillating vessel, comprising in combination a gyroscope, supporting means for said gyroscope which permits a forward and rearward movement of the spinning axis thereof in a predetermined path with respect to the oscillating vessel, and means moving relative to the vessel for imparting to the axis of the gyroscope movement at intervals corresponding to the periodicity of the oscillating vessel.
23. Means for applying gyroscopic forces to an oscillating vessel, comprising in combination a gyroscope, supporting means for said gyroscope which permits a forward and rearward movement of the spinning axis thereof in a predetermined path with respect to the ship, and means moving relative to the vessel for imparting to the axis of the gyroscope movement at intervals corresponding to the periodicity of the oscillating vessel.
24. Means for applying gyroscopic forces to an oscillating vessel comprising in combination a plurality of gyroscopes mounted for angular movements relative to the oscillating vessel, power means for causing and controlling the said angular movements of the gyroscopes, and common automatic actuating means for said power means adapted to cause the gyroscopes to operate in synchronism with each other and with the periodicity of the oscillating vessel.
25. The combination with a structure in stable equilibrium, of a gyroscope mounted thereon for swinging movements relative thereto, power operated means for swinging the gyroscope, and an automatic actuator for the power operated means acting at such times as to cause the effect of the gyroscope to supplement the natural forces tending toward stable equilibrium.
26. The combination of a structure having a substantially definite period of oscillation, a gyroscope secured to said structure for oscillating movements relative thereto,—the plane of oscillation of the gyroscope being at an angle to the plane of oscillation of the structure,—and power operated means controlling the oscillating movements of the gyroscope, the period of oscillation of the gyroscope being substantially synchronous with the period of oscillation of the structure, so that the moments of quiescence of the two oscillating elements substantially coincide in the cycle of operations.
27. In combination with a structure to which gyroscopic forces are to be applied, a gyroscope, a casing surrounding and inclosing said gyroscope, trunnions on the casing at right angles to the axis of the gyroscope for supporting it for swinging movements relative to the structure, a precession engine, and mechanical means connecting said engine and said casing whereby the casing may be swung upon its trunnions.
28. The combination of a structure to which gyroscopic forces are to be applied,

- said structure being capable of oscillation, a gyroscope arranged for precessional movements relative to the structure, power means for controlling the precessional movements 5 of the gyroscope, and an automatic actuator for said power means adapted to cause a precessional movement of the gyroscope to continue until the direction of swing of the oscillating structure reverses, whereupon the 10 automatic actuator is adapted to stop and reverse the precessional movement of the gyroscope.
29. In a gyroscopic mechanism for oscillating structures, the combination of a gyroscope mounted for precessional movements, power operated means causing the precession, controlling devices controlling the flow of power to the power operated means, and a sensitive actuator responsive to incipient 15 oscillations of the structure.
30. In a gyroscopic mechanism for oscillating structures, the combination of a gyroscope mounted for precessional movements, a precession engine causing the precession, 20 means controlling the precession engine and arranged to be automatically responsive to start the precession upon incipient oscillations of the structure irrespective of the distance from mid-position at which a swing of 25 the structure starts.
31. In an automatic actuator for gyroscopes, a pendulum, a structure adapted to move relative to the pendulum, contacts on the pendulum and on the structure, the contact on the structure being movable on the structure so that it may follow the movement of the contact on the pendulum, in order 30 that the actuator shall respond to incipient movement between the structure and the pendulum at any position.
32. In an automatic actuator for gyroscopes, the combination of a pendulum, a structure adapted for oscillatory movements relative to the pendulum, contacts on the 35 pendulum and structure adapted to reverse the control effect upon reversal of the movement of the structure.
33. In an automatic actuator for gyroscopes, the combination of a pendulum, a structure adapted for oscillatory movements relative to the pendulum, electrical contacts 40 between the pendulum and the structure arranged to be connected on slight relative movement between the pendulum and the structure, the contacts on one of the two parts being arranged to travel relative to that part, so that the electrical contacts remain in close juxtaposition while the structure may have extended movement relative 45 to the pendulum.
34. The combination of a gyroscope, a plurality of frames by which the gyroscope is universally mounted for precessional movements in any direction, mechanical 50 means for tilting said frames relative to each other, brakes for retarding the motion of said frames, and means controlling the operation of the said mechanical means and the brakes.
35. In a gyroscope for universal movement, the combination with a tiltable structure, of a gyroscope, a plurality of frames connected at angles to each other by which the gyroscope is universally mounted upon the structure, a precession engine mounted 70 to tilt with the structure, and mechanical means connecting the precession engine with the innermost one of the plurality of frames whereby precessional movements may be communicated to the gyroscope within the 75 inner frame.
36. The combination, with a marine vessel, of controllable means operating in alternate directions on the vessel for imparting a rocking or oscillating movement thereto, 80 and mechanism whereby said means is caused to reverse the direction of its action upon the vessel at regular and predetermined intervals of time.
37. The combination, with a marine vessel, of controllable means operating to impart a rocking or oscillating movement to the vessel, and mechanism whereby said means is caused to reverse the direction of its action upon the vessel at intervals corresponding 85 to the periodicity of the vessel in actual service.
38. The combination, with a marine vessel, of controllable means for imparting a rocking or oscillating movement to said 90 vessel, and mechanism whereby said means is caused to reverse the direction of its action upon the vessel at regular and predetermined intervals of time.
39. The combination, with a marine vessel, of a gyroscope, and means for moving its spinning axis in a substantially fixed path with respect to the vessel and at intervals corresponding to the periodicity thereof. 95
40. The combination, with a marine vessel, of a plurality of gyroscopes and means, independent of the action of the vessel, for moving their spinning axes in a substantially fixed path with respect to the vessel and at intervals corresponding to the periodicity thereof. 100
41. The combination, with a marine vessel, of a gyroscope mounted in the vessel, a casing within which the gyroscope is capable of spinning and having trunnions extending from its sides the axis of which is at right angles to the spinning axis of the gyroscope, a bracket located on each side of the gyroscope casing within which is journaled one of the trunnions of the gyroscope 110 casing, and mechanism moving relative to the vessel for locking the gyroscope casing upon its trunnions.
42. The combination, with a marine vessel, of a gyroscope having its spinning axis 115
- 120
- 125
- 130

vertical when in central position, a casing for the gyroscope having trunnions projecting from its sides at right angles to the spinning axis of the gyroscope and extending transverse the vessel and mounted within brackets, and mechanism moving relative to the vessel for swinging the spinning axis of the gyroscope a varied number of degrees each side of its vertical position.

10 43. The combination, with a marine vessel, of a gyroscope, supporting means for said gyroscope which permits a forward and

rearward movement of the spinning axis thereof in a fixed path with respect to the vessel, and means for imparting to the axis 15 of the gyroscope, movement at intervals corresponding to the periodicity of the vessel.

In testimony whereof I have hereunto set my hand in presence of two subscribing witnesses.

ELMER A. SPERRY.

Copies of this patent may be obtained for five cents each, by addressing the "Commissioner of Patents.
Washington, D. C."

It is hereby certified that in Letters Patent No. 1,150,311, granted August 17, 1915, upon the application of Elmer A. Sperry, of Brooklyn, New York, for an improvement in "Ships' Gyroscopes," errors appear in the printed specification requiring correction as follows: Page 10, line 80, claim 23, for the word "ship" read *oscillating vessel*; page 11, line 127, claim 41, for the word "locking" read *rocking*; and that the said Letters Patent should be read with these corrections therein that the same may conform to the record of the case in the Patent Office.

Signed and sealed this 28th day of September, A. D., 1915.

[SEAL.]

J. T. NEWTON,

Acting Commissioner of Patents.
